UNITED STATES PATENT OFFICE.

CLAIR WHITE, OF SMETHPORT, PENNSYLVANIA.

T-SQUARE HOLDER.

977,765.

Specification of Letters Patent.

Patented Dec. 6, 1910.

Application filed March 23, 1910. Serial No. 551,078.

To all whom it may concern:

Be it known that I, CLAIR WHITE, a citizen of the United States, residing at Smethport, in the county of McKean and State of Pennsylvania, have invented certain new and useful Improvements in T-Square Holders, of which the following is a specification.

This invention comprehends certain new and useful improvements in drafting instruments or appliances and relates particularly to T-square holders.

The invention has for its primary object a simple, durable and efficient construction of device designed to be fastened to the end 15 of a T-square and so adjusted as to clamp on the end of the drafting board to securely hold the T-square in position thereon, and the invention consists in certain constructions and arrangements of the parts that I 20 shall hereinafter fully describe and claim.

For a full understanding of the invention, reference is to be had to the following description and accompanying drawings, in which:

25 Figure 1 is a perspective view of my T-square holder showing the application thereof; Fig. 2 is a top plan view of the device on an enlarged scale; and, Fig. 3 is a side portion thereof.

30 Corresponding and like parts are referred to in the following description and indicated in all the views of the drawings by the same reference characters.

35 My improved T-square holder embodies a base plate 1 which is formed at its corners for instance with holes designed to receive screws or other fastening devices for securing the appliances on a T-square. The base plate 1 is formed at opposite side edges with 40 upstanding apertured ears 2 through which a stem or spindle 3 extends. A clamping arm 4 is formed at one end with an upstanding apertured lug 5 rigidly secured to one end of the stem 4, as by upsetting the end of 45 the stem, and the clamping arm 4 is downwardly off-set or deflected near its opposite end, as indicated at 6, and is formed at such end with a head 7, the upper or main portion of which lies in a plane below, but par-

50 allel with the lower face of the base plate 1, as clearly illustrated in the drawings. The head 7 is formed with a right angularly disposed flange 8 and the flange is in turn formed with hooked lugs 9, two of these lugs

being shown in the present instance, spaced 55 laterally from each other.

The head 7, as is apparent, is intended to engage the edge of a drafting board, table, or the like, and hence in order to hold the clamping arm under tension, a spring 10 is 60 coiled around the stem 3 between the foremost ear 2 and a collar 11 or the like secured in any desired way to the stem. At its rear end the stem 3 is provided with a finger piece 12. 65

From the foregoing description in connection with the accompanying drawing, the operation of my improved T-square holder will be apparent. In the practical use of the device the base plate 1 is secured to the 70 end of a T-square, the clamping arm 4 projecting beyond said end, as shown, and the off-set head of the clamping arm being engaged with the adjoining edge of the board on which the T-square is laid, the arm being 75 held under tension and thereby securely holding the T-square in place. Obviously, the device can be very cheaply manufactured and easily applied and manipulated.

Having thus described the invention, what 80 is claimed as new is:

As a new article of manufacture, the herein described T-square holder comprising a base plate formed at opposite edges with upstanding apertured ears, a stem passing 85 through the apertures of the ears, a spring coiled around said stem between the ears and bearing against one ear, a collar secured to said stem and engaged by said spring, a clamping arm provided at one end 90 with an upstanding apertured lug by which it is secured to the foremost end of the stem, the arm being downwardly deflected near its opposite end and formed at said end with a head which extends in a plane off-set from, 95 but parallel to the lower face of the base plate, said head being formed with a right-angularly disposed flange, and the flange being formed with engaging lugs, and a finger piece secured to the opposite end of the 100 stem.

In testimony whereof I affix my signature in presence of two witnesses.

CLAIR WHITE. [L. S.]
